UNITED STATES PATENT OFFICE.

WILLIAM HENRY ILLINGWORTH, OF HALIFAX, ENGLAND.

ELECTRICAL CUT-OUT.

Application filed October 5, 1920. Serial No. 414,913.

To all whom it may concern:

Be it known that I, WILLIAM HENRY ILLINGWORTH, a subject of the King of Great Britain, residing at 1 Ruskin Terrace, Lee 5 Mount, Halifax, in the county of York, England, have invented certain new and useful Improvements in Improved Electrical Cut-Outs, of which the following is a specification.

10 This invention relates to a non-fusible electrical cut-out that is specially applicable to distribution boards of small amperage for electrical lighting circuits, but may be used on any other electrical circuit in which a 15 small amperage is used, the chief object being to do away with fuse wires, and their replacement and the risk of injury when a thicker wire, or one having a higher fusing point is substituted for the correct wire, also 20 to do away with arcing and avoid a sudden surge of current on a dead short circuit.

According to this invention a column of mercury restricted at some portion of its length forms an electrical connection between two contacts but parts at the restricted portion when the current reaches a predetermined amperage. The gas generated by vaporization of the mercury escapes to the atmosphere through one or more apertures in a chamber containing a plunger and the mercury that has been thrown out of the passage above the restricted portion collects in the form of a small globule in a cup, or basin, at the top of the passage. To 30 make the contact the plunger is depressed against the action of a spring and as soon as it enters the basin it forces the mercury back into the passage.

In the accompanying drawings:—

40 Figure 1 is a section of a cut-out constructed in accordance with this invention.

Figure 2 is an elevation of a cap or cover for the same.

Figure 3 is a similar view to Figure 1 showing a modified construction of cut-out.

Figure 4 is a view of a distribution board with the cover removed.

Figure 5 is a front view of the rear portion of a porcelain insulating holder.

50 Figure 6 is an end view and Figure 7 a plan of a complete unit, and

Figure 8 is a transverse section of the insulating holder.

Figure 9 is a section showing a slightly modified construction of unit and pump.

Referring to Figures 1 and 2 the column

of mercury is contained in a tube A of any suitable known insulating material, or composition, that is preferably of a refractory nature. The passage for the column of mercury is shown restricted at a, the diameter and length of the passage and the distance at which it is placed from the top of the tube determining the amperage at which the column will part. The tube is formed with a collar a¹ to form an abutment a² for two metal thimbles, or fittings B, B¹, which carry the top and bottom contacts C, C¹, respectively. Each fitting is made with a socket b adapted to fit tightly upon its respective end of the tube and to be pressed up to the collar. The contact C is constructed from copper and made in the form of a cup or basin with a short length of tube c to enter a hole in the top of the insulating tube, until it meets the restricted passage a, the diameter of the hole in the copper tube being slightly larger than the latter. Projecting from one side of the basin is an arm c¹ which projects through the side of the fitting and carries a binding screw c², or any other suitable terminal. The portion of the fitting above the basin constitutes a cylindrical chamber b¹ having one or more vent apertures b² and on the top of this chamber, a cap b³ is detachably secured. This cap is formed with a central aperture b⁴ for the passage of a sleeve D in which a plunger E is free to work and is made of suitable diameter to enter the cup. The sleeve is formed with a collar d to fit the chamber and such collar is formed with one or more nicks d¹ to allow air to pass by it when the sleeve is depressed. The sleeve has a bevelled edge d² adapted to bear against a seating b⁵ when the sleeve is depressed and such sleeve is normally retained in its outer position by a spring d³. The plunger is provided with a radial pin e which projects through a slot d⁴ in the sleeve and is retained in its outer position by a spring e¹ interposed between the sleeve and a knob e². When the plunger is depressed it first lowers the bevelled edge of the sleeve onto its seating so forming a closure for preventing escape of mercury, the plunger then enters the cup and returns the globule of mercury which has been thrown out of the tube by the parting of the column, back into the tube and so remakes the column and contact. The lower contact C¹ comprises a copper rod which fits for a portion of its length a passage of en-

larged diameter in the insulating tube and may be formed at its lower end with a head c^3 which fits tightly into a recess formed in the metal fitting B^1 . The rod is reduced 5 in diameter at c^4 to form an annular cavity a^3 for the passage of mercury and so ensure good surface contact. In the construction shown in Figure 3 the metal fittings B , B^1 are dispensed with, the whole of the body 10 portion B^x being constructed from one piece of mouldable insulating material with the upper contact embedded in it. In applying the invention to a distribution board which may for example be used in connection with 15 an electric lighting circuit, the head of each lower contact is formed with a groove c^5 to receive a bus bar c^6 (Fig. 4) which is clamped to it by a cap c^7 having a similar groove c^8 , and connected to the lower portion 20 of the metal fitting or insulating tube by screws c^9 . Any other suitably shaped bus bar may be used in place of a round one. In the distribution board shown in Figure 4 each tube or cartridge A' is clamped between 25 two porcelain, or other insulating holders F , F^1 , by bolts f and milled nuts f^1 . The bolts f secure the rear portions of the holders to the casing and the milled nuts f^1 can be actuated to perform the clamping operations, 30 or be removed to enable the front portion F to be taken off without disturbing the rear portion. The front portion can be marked with the particular circuit that that particular cut-out controls, it also serves to cover 35 the metallic, or live part of the cartridge. Each portion is grooved at f^2 Figures 5, 6 and 8 for the passage of the bus bar c^6 and the lower end of the front portion is formed 40 with a tongue f^3 to cover the lower end of the cartridge. Extending along the top of the rear portion is a rib f^4 with an opening f^5 for the passage of a wire c^{10} to the terminal c^2 and behind such rib is a channel f^6 in which the various wires lie. c^{11} indicates 45 a main cable one of which is connected to each bus bar, c^6 . In the form shown in Figure 4 the two sections of the casing which grip the bus bar are shown as provided with lateral lugs which are connected 50 together so that the fastening screws or connecting pins are above the plane of the bottom of the case.

In the modification shown in Fig. 9 the pump is placed at the front of the unit below the restricted passage a . This pump is so arranged that when the plunger E is depressed it forces the mercury vapour or air out of the passage a and fills such passage with mercury which also flows into the chamber b^1 , the return stroke of the plunger sucking the mercury back through the passage a until it occupies its normal position therein, leaving sufficient mercury at the top of the tube to make contact with the top contact C . When the pump is placed below the

level of the mercury either to one side or at the bottom of the unit means must be provided for preventing leakage of mercury. For this purpose the plunger E is supported at one end in a barrel or casing e^2 and at the other end by a cap e^4 which is detachably connected with such casing. The latter is formed with a conical seating e^5 to receive packing material e^6 . This material is retained in a state of compression around the 70 plunger E by a spring e^7 bearing against a collar e^8 that is loosely mounted on the plunger and against a collar e^9 that is rigid therewith. The spring e^7 normally retains the plunger at the outer end of its stroke and a knob e^{10} on the outer end of the plunger limits the amount of its inward traverse. The apparatus described may be used in conjunction with switches, wall plugs, or other small electrical apparatus requiring 75 protection by fuses. It may be enclosed in a casing of porcelain with an ironclad casing outside and the knob of the plunger projecting outside the casing. It can also be used for house work to protect supply companies' mains, or for any other purpose 80 where fuses are required at the present time. The amperage can be increased by arranging the columns in parallel, or by altering the position, diameter and length of the restricted passage, or it can be reduced by 85 altering the position, diameter and length of restricted passage in a single column to as low as .5 of an ampere. Its action is so instantaneous that it is impossible to have 90 a fire.

I claim:—

1. In an electrical cut-out, a tube of insulating material having a passage for a column of mercury, the said passage being 105 restricted at some intermediate portion of its length and having its upper aperture sufficiently small to prevent mercury flowing in and filling the passage by gravity, a cup situated at the top of the passage, a chamber surmounting said cup, and apertured to the atmosphere, a plunger mounted in the chamber and adapted to enter the cup, a contact situated in the cup and having a tubular extension adapted to enter the passage in the tube and an arm branching through the side of the latter, a contact closing the bottom of the tube and having its inner end reduced in diameter to form an annular passage for mercury.

2. In an electrical cut-out, a tube of insulating material having a passage for a column of mercury, the said passage being restricted at some intermediate portion of its length and having its upper aperture sufficiently small to prevent mercury flowing in and filling the passage by gravity, a chamber situated above the passage and apertured to the atmosphere, a lid detachably connected with the chamber, a sleeve 115

slidably mounted in the lid and having a flange adapted to fit the bore of the chamber, a spring interposed between the flange and the bottom of the chamber which constitutes a seating for said sleeve, a plunger slidably mounted in the sleeve and connected therewith through a pin and slot connection, a spring for normally retaining the plunger in its retracted position, a cup shaped contact situated at the top of the tube with an arm projecting outside the tube, a contact closing the bottom of the tube and having its inner end reduced in diameter to form an annular passage for mercury, and means for connecting conductors with said contacts.

3. In an electrical cut-out, a tube of insulating material having a passage for a column of mercury, the said passage being restricted at some portion of its length and having its upper aperture sufficiently small to prevent mercury flowing in and filling the passage by gravity, two contacts communicating with said passage, a plunger for forc-

ing mercury into the latter, an insulating holder comprising a front part and a back part adapted to enclose the tube and contacts and leave the plunger exposed for operating purposes, the lower end of the front portion being formed with a tongue and the lower end of the back portion with a recess to receive same, the upper end of the back portion being recessed at the back and continued upwardly in the form of a rib which projects above the top of the back portion and is recessed transversely, the front portion of the holder having a plain surface to act as a tablet which can be marked with the particular circuit that the cut-out controls, means for clamping the holder to a base and means for clamping the tube between the two portions of the holder in such manner that the front portion can be removed without affecting the connection which connects the rear portion to the base.

In testimony whereof I affix my signature.

WILLIAM HENRY ELLINGWORTH.
